WINDOW LOCKING DEVICE

John Megela, New York, N. Y.

Application August 23, 1940, Serial No. 353,799

1 Claim. (Cl. 292—251)

This invention relates to locking devices for double-hung sash windows and similar structures.

The principal object of the invention is to simplify and improve the construction and manner of operation of window locking devices whereby these devices may be economically produced and readily installed, and whereby windows so equipped may be securely locked, in either of a plurality of positions, to prevent ingress.

The object of the invention is attained, according to one feature thereof, by the provision of a locking device that comprises two inexpensive elements, each of which may be readily installed with a minimum exercise of mechanical skill, whereby the sashes of a double-hung window may be securely locked together in either of a plurality of positions to prevent unauthorized movement of either thereof, either when the window is closed, or when the window is opened for ventilating purposes. Another feature of the invention is to provide means whereby the sashes, when locked in closed position, are so closely drawn together as to prevent the insertion of prying tools. Another feature of the invention is to provide means automatically to align the elements of the locking device to facilitate the locking of the window in its closed position, or in either of a plurality of open positions. A further feature of the invention is to provide a simple disabling means to render the locking device ineffective when its action is not required. Other features of the invention will be apparent from the specification.

A preferred form of the invention is shown in the appended drawing, in which

Fig. 1 is a front elevation of the invention attached, in operative position, to the sash members of a double-hung window;

Fig. 2 is a sectional elevation of the invention, taken along the line 2—2 of Fig. 1, showing the elements in locking position;

Fig. 3 is a sectional elevation of the invention, showing the elements in their disabled position.

In the embodiment shown in the drawing, one element of the invention comprises a housing 10 (see Figs. 1 and 2) having a base portion provided with holes, countersunk to permit the insertion of screws, whereby the housing may be securely fastened to the top of the upper cross bar of the lower sash 5 of a double-hung window. The front and rear walls of housing 10 are provided with apertures 11 and 12, respectively, which serve as bearings for a plunger 13, slidably

mounted therein. The forward end of plunger 13 is provided with a flattened portion 14 to facilitate manual rotation of the plunger, and a concentric shoulder 15 adapted to coact with the forward wall of housing 10, as hereinafter described. On the portion of plunger 13 within the housing is fixed a collar 16 that serves as an abutment for a helical compression spring 17 that also bears against the inside face of the forward wall of the housing, whereby the plunger is constantly urged rearwardly. The rearward end of plunger 13 is provided with a threaded portion 18 having a root diameter slightly in excess of the diameter of the plunger.

The second element of the invention comprises a bar member 20 secured by screws to the inner face of a vertical side rail of the upper sash 6, and of such thickness that the distance between its outer face and the rear wall of housing 10 is slightly greater than the threaded portion of plunger 13. Bar member 20 is provided with a plurality of threaded holes 21, spaced at desired intervals, each of which is adapted to receive the threaded portion 18 of plunger 13. Member 20 is so positioned on the upper sash that the lowermost hole 21 is in horizontal alignment with plunger 13 when the window is closed, and the remaining holes 21 are in vertical alignment therewith.

By means of the above described novel arrangement, the upper and lower sashes, when closed, may be securely locked together merely by rotating plunger 13 by means of flattened portion 14. The several parts are so designed that after threaded portion 18 advances slightly into the lowermost hole 21, shoulder 15 abuts the outer face of the forward wall of housing 10 so that continued rotation of the plunger serves to take up the clearance that invariably exists between the sashes in windows of this type, and the sashes are drawn into contact with each other. Due to the substantial mechanical advantage attained by the use of a screw, a slight additional pressure on plunger 13 serves not only to prevent rattling, but also makes it virtually impossible to insert a prying tool between the sashes.

In the event the window is to be left open to provide for ventilation, threaded portion 18 of plunger 13 may be engaged with either of the upper holes 21 in bar 20. Although the cross-bars of the sashes are not in juxtaposition in either of these settings, a reasonable pressure applied to flattened portion 14 serves, as above, to hold the sashes stationary relative to the window frame due to the fact that the vertical

rails of the sashes exert a substantial gripping action on guide rail 7 of the window frame. Thus, although the window may be opened from the top and bottom simultaneously, the sashes cannot be moved to increase the opening at either end to permit manipulation of the locking device from the outside. Obviously, the extent of relative movement of the sashes permitted by the uppermost hole 21 must be sufficiently limited to prevent access between either sash and the window frame, regardless of the positions of the sashes.

In order to facilitate the alignment of plunger 13 with the holes 21, the rearward end of the threaded portion 18 is slightly tapered, as at 19. Then, to effect locking, plunger 13 is withdrawn against the tension of spring 17 and one sash is moved to place the desired hole in approximate alignment with the plunger, whereupon the plunger is released and is urged against the face of bar member 20 by spring 17. The movement of the sash is then continued until the plunger snaps into the desired hole 21. The sashes are thus accurately aligned to permit the locking thereof by rotation of the plunger.

In the event the action of the locking device is not required, means are provided to render it ineffective and to permit unimpeded movement of either sash. For this purpose aperture 12 of housing 10 is tapped to receive the threaded portion 18 of plunger 13. When the locking device is to be disabled, plunger 13 is drawn rearwardly, against the tension of spring 17, until the forward end of threaded portion 18 abuts the outer face of the rear wall of housing 10. Plunger 13 is then rotated slightly counter-clockwise to engage threaded portion 18 with the tapped aperture in housing 10. The plunger is thereby held in disabled position (as in Fig. 3), and,

due to the spaced relationship of housing 10 and bar member 20, unimpeded movement of either sash may be effected.

While I have described what I consider to be a highly desirable embodiment of my invention, it is obvious that many changes in form may be made without departing from the invention.

What I claim as new, and desire to secure by Letters Patent, is:

10. A locking device for double-hung sash windows comprising the combination of a plunger housing fixed to the top of the upper rail of the lower sash, a plunger slidably mounted in said housing, said plunger being provided at one end with a threaded portion and at the other end with a flattened portion to permit manual rotation of the plunger, said plunger at its threaded end being adapted to engage a bar member spaced from said housing a distance greater than the threaded portion of said plunger, said bar member being fixed to the inner face of a side rail of the upper sash and being provided with a plurality of vertically aligned threaded holes adapted to receive the threaded portion of the plunger, means to engage said plunger with either of said holes, said last recited means comprising impositive means to urge said plunger against said bar member and a tapered end on the threaded portion of said plunger, a shoulder on said plunger arranged to abut said housing after said threaded portion is engaged with one of said plurality of threaded holes, whereby continued rotation of said plunger is effective positively to draw said sashes together, and means to render said locking device ineffective comprising a tapped portion in said housing adjacent to and adapted to receive the threaded portion of said plunger.

JOHN MEGELA.
